EARL G. PERKINS, OF YOUNGSTOWN, OHIO; FLORENCE M. PERKINS ADMINISTRATRIX
OF SAID EARL G. PERKINS, DECEASED.

CARBON-FEEDING MECHANISM FOR ARC LAMPS.

Application filed July 18, 1922. Serial No. 575,874.

This invention relates to arc lamps, and more particularly to lamps of the twin or multiple type having a joint or common control for the carbons.

One of the objects of the invention is to provide a mechanism for exerting a direct lift on the carbons for the purpose of separation to produce the arc. That is to say, one of the novel and distinctive features of the invention is to provide lifting means for the carbons, a portion of which operates in the same vertical plane and on the same center line as the carbons to be lifted.

Another object of the invention is to provide means for effecting a slow, uniform separation of the carbons, thus giving the carbon points full opportunity to heat before the strength of the current is reduced by the full separation of the carbons. In other words, the present invention aims to provide means for building up the arc slowly and gradually, rather than by a sharp, sudden separation of the carbons, thus allowing ample time to heat, and avoiding the usual flashing and sputtering which ordinarily attends the building up of an arc. In that connection the invention proposes to utilize a yieldingly mounted solenoid unit which materially assists, in combination with the other instrumentalities of the invention, to obtain the desired relatively slow separation of the carbon points.

With the above and other objects in view which will more readily appear as the nature of the invention is better understood, the same consists in the novel construction, combination and arrangement of parts, hereinafter more fully described, illustrated and claimed.

A preferred and practical embodiment of the invention is shown in the accompanying drawing in which—

Figure 1 is a front elevation showing the mechanism of my invention in operative position.

Figure 2 is a vertical sectional view taken on the line 2—2 of Figure 1.

Figure 3 is a vertical sectional view taken on the line 3—3 of Figure 1.

Figure 4 is a view similar to Figure 1, but showing the mechanism in inoperative position.

Figure 5 is a horizontal sectional view taken on the line 5—5 of Figure 1.

Figure 6 is a horizontal sectional view taken on the line 6—6 of Figure 1.

Figure 7 is an enlarged detail sectional view illustrating the yielding coupling between the solenoid and the flexible connections for operating the lifting mechanism when in inoperative position.

Figure 8 is a similar view illustrating the same parts just after the solenoid is energized and the armature commences to travel downwardly.

Figure 9 is a similar view illustrating the same parts when the mechanism is in full operative position.

Similar reference characters designate corresponding parts throughout the several figures of the drawings.

In carrying the invention into effect it is proposed to provide a novel operating mechanism, designated generally as A, for engaging and lifting the carbons, together with a novel actuating unit in the form of a yieldingly mounted solenoid device B, which cushions the movement of the solenoid when it is energized, as well as when it is de-energized upon the breaking of the circuit. By this novel combination and arrangement, as well as by the location and distribution of the instrumentalities for lifting the carbons, the building up of the arc is slowly and gradually accomplished.

Referring now more particularly to the operating mechanism A, and parts associated therewith, it will be observed that there is provided a suitable frame including a lower base plate 1, an upper cap plate 2, and the supporting columns 3, the inner face of each plate being provided with suitable sockets for receiving and anchoring the ends of the columns 3. The cap plate 2 carries four depending lugs 4, each of which is provided near its lower end with a journal opening in which are mounted oppositely located and parallel arranged rocker shafts 5, each of which carries at its intermediate portion a single outwardly extending crank arm 6. Also rigidly attached to each end of each rocker shaft 5, by means of an insulating sleeve or ferrule 7, is a bifurcated inwardly extending rocker arm 8 of shorter length than arm 6.

As clearly shown in Figure 4, the diameter of the sleeve 7 is greater than that of the rocker arm 5 and forms an abutting

shoulder 7^a to engage the lug 4, thus holding the shaft 5 against longitudinal movement, as well as insulating the two bifurcated rocker arms from each other.

- 5 Swingly connected with the free end of each bifurcated rocker arm 8 is a link 9, the upper end of which is also swingingly connected with a yoke or cross-head 10 carried at the upper ends of the lifting rods 11.
- 10 These lifting rods 11 carry at their lower ends another cross head or yoke 12 having hinged thereto a suitable carbon clutch 13. Slidably mounted upon the lifting rods 11 is a carbon carrier 14 having a central opening adapted to receive the upper carbon stick 15, which may be locked therein by means of a thumb screw 16 or its equivalent.

With the arrangement described, it will be apparent that the lifting means for the upper carbons 15 is arranged in such manner that the lifting force is exerted in direct alignment with, and in the same vertical plane as, the carbons.

- 20 As previously pointed out, the crank arms 6, which are connected with the solenoid B as will hereinafter more fully appear in detail, are longer than the arms 8 and therefore ample power is transmitted to the links 9 connecting with the intermediate portion 30 of the yoke piece 10 to easily lift the rods 11. This organization of parts constitutes one of the novel and distinctive features of the present improvement, and provides a well balanced and stable construction, which 35 reliably and effectively functions under the actuating influence of the solenoid unit B.

In connection with the solenoid unit B, which also constitutes a further novel and distinctive part of the present invention, it 40 will be observed that the same is slidably and yieldingly mounted upon the supporting columns 3 in such manner that it will move upwardly when energized, thus relieving the operating connections of the sudden shock 45 which would be incident to their use with a stationary solenoid.

- 50 While it is, of course, possible to mount the solenoid in various ways, a practical form of mounting is illustrated in the drawings, from which it will be observed that duplicate plates 17 and 17' are provided with the notched portions 17^a for slidably engaging with the standards 3. These plates 17 and 17' have arranged therebetween the 55 solenoid 18 and are securely held together by the tie-rods 19. And for the purpose of insulating the lifting rods 11, clutch 13 and carbon 15 from the frame, an insulating disk 19^a having a central carbon guiding opening is employed.

Mounted upon the columns 3 between the plates 17 and 17' are two sets of coil springs 20 and 20', whose outer ends abut against the plates while the inner ends engage with 60 a pin 21 or other suitable abutments on the

rods so that the plates 17 and 17' are yieldingly supported on the columns.

This method of mounting the solenoid not only tends to soften and relieve the shock and strain incident to operation, but also 70 makes the changing of solenoids a very simple matter. When the nuts on the tie-rods are loosened, the plates 17 and 17' will move away from each other under pressure of springs 20 and 20', after which the solenoid 75 may be lifted out and a new one set in, and turning up the nuts finishes the operation.

Reciprocatingly mounted within the solenoid 18 is an armature 22 the upper end 23 of which carries a cross head 24 having attached thereto a relatively thin metal strip or plate 25 carrying at each end an upstanding pin or post, preferably in the form of a headed bolt 26, upon which is slidably mounted a cross-bar 27. Upon each of the 80 bolts 26, between the head thereof and the cross-bar 27, is a coil spring 28, the purpose of which is hereinafter explained. As will be observed from Figures 2, 6 and 7, the cross-bar 27 has pivotally connected to its 85 central portion a piston rod 29 having at its upper end a piston head 30 slidably mounted in a dash pot 31 suspended from the cap plate 2.

The bolts 26, cross-bar 27, and springs 28 90 constitute a relatively yielding or elastic coupling device, designated generally as C, for connecting the armature 23 with the crank arms 6 through the medium of the flexible connections 32. Thus, in addition to 95 providing a yieldingly mounted solenoid unit B, a yielding coupling C is provided between the solenoid and the crank arms 6, which materially contributes to the cushioning and shock absorbing features of the 100 device.

Depending from the base plate 1 is a supporting rod 33 carrying at its lower end an adjustably mounted cross bar 34, which is held in any desired position on the rod by 105 means of a thumb screw 35, the end of which engages in a slot 35^a, thereby insuring perfect alinement of the cross-bar 34. At each end the said cross-bar 34 is provided with a carbon carrier 36 which receives the lower carbon 37 and is provided with a thumb screw 38 for rigidly holding the carbon in place.

With reference to the general operation of the device, it may be pointed out that when 110 the lamps are not burning the relative position of the yielding coupling device C and the solenoid 18 is as shown in Figure 7. When the solenoid is energized the armature 22 will travel downwardly, drawing 115 with it the metal strip 25, attached to the cross-head 24, and the posts 26, compressing the springs 28 against the cross-bar 27 (see Figure 8) until the pressure of the springs 120 is sufficient to rock the arms 5 against the 130

resistance of the lifting mechanism. At this point, while the armature continues to travel downwardly, the springs 28 will begin to expand, thus gently forcing the cross-bar 27 downwardly somewhat faster than the travel of the armature, so that when the armature reaches the limit of its travel, the relative position of the parts will be as shown in Figure 9, and the arc will be built up and the lamps burning.

As the bifurcated rocker arms 8 and crank arms 6 have a fixed radial position on the shafts 5, the downward movement of the arms 6 will cause the outer ends of the arms 8 to move upwardly, and, through the medium of the links 9 between the rocker arms and the yoke 10, cause the lifting rods 11 to also move upwardly. As this upward movement of the lifting rods takes place, the clutch 13 will engage the upper carbon stick 15 and gradually separate it from the lower carbon stick, thus building up the arc. (See Figures 1 and 3.)

In connection with the movement of the bifurcated rocker arms 8 to lift the links 9, it is pointed out that these arms act as guides within which the lifting rods 11 must move upwardly in a straight line without swaying or swinging. This has the beneficial result of causing the upper carbon to move upwardly in a positively straight line, thereby insuring perfect alinement of the upper carbon with the lower carbon at all times, regardless of the length or position of either.

Because of the fact that the speed of travel of the armature 22 gradually decreases as it passes into the solenoid by reason of the corresponding decrease in the magnetic energy acting upon it, due to increasing arc length, it will be apparent that the tendency of the shafts 5 to move faster near the ends of their arcs of movement is counteracted or equalized, so that a substantially uniform rate of movement is imparted to the rocker shafts during the entire movement of the armature, thus assuring a steady, gradual, uniform movement of the carbon electrodes while building up the arc.

Also, as previously indicated, the bifurcated rocker arms 8 are shorter than the crank arms 6, by reason of which it is obvious that the lifting rods 11 will travel a shorter distance than that traveled by the armature in the solenoid, the ratio adopted being substantially 1 to 2. By reason of this arrangement, slight changes in the position of the armature, due to fluctuations in the voltage, produce little or no effect in the arc, thus adding stability and uniformity to the functioning of the latter on unstable power lines.

The coil springs 28 mounted upon the posts 26 also add to the stability and uniformity of the functioning of the arc, as

these springs must be compressed to the point of sufficient resistance before the movement of the armature is communicated to the cross-bar 27, and through it and intervening connections to the carbon sticks. In other words, the downward pressure upon the cross-bar 27, caused by the downward movement of the armature, is applied through the springs 28. This is especially important in the use of an alternating current, where vibrations are more pronounced.

Another function of springs 28, acting in conjunction with springs 20 and 20' is to produce a steady, smooth initial separation of the carbon points. When the solenoid is energized and commences to exert its magnetic influence upon the armature, the tendency of the former will be to move upwardly, which it will do slightly until the resistance of the lower springs 20' is sufficient to check such movement. Likewise, a similar action of the upper springs 20, also in conjunction with springs 28, will relieve the jar or shock of operation when the solenoid is de-energized.

Without further description it is thought that the features and advantages of the invention will be readily apparent to those skilled in the art, and it will, of course, be understood that changes in the form, proportion and minor details of construction may be resorted to without departing from the spirit of the invention or scope of the appended claims; and it will be further understood that while the novel resilient or yieldable mounting of the solenoid possesses special utility in its application to a carbon feed mechanism for arc lamps, this phase of the invention is susceptible of broader application where a solenoid mounting of that character could be advantageously employed with other devices and mechanisms to be actuated therefrom.

I claim:

1. In an arc lamp, carbon lifting means comprising a rectangular open frame having carbon engaging means, a pair of rocker shafts arranged at the upper end of the frame, offset lifting arms carried by said rocker shafts, links connecting the lifting arms with an upper transverse portion of said frame, and a solenoid unit for actuating said rocker shaft.

2. A carbon feeding mechanism for arc lamps including carbon lifting means consisting of a pair of rods, upper and lower cross pieces connecting said rods, a rocker shaft disposed at right angles to the rods, a rocker arm disposed radially with reference to the rocker shaft, a link connecting the outer end of the rocker arm and intermediate portion of the upper cross piece connecting the rods, and a solenoid unit for actuating said rocker shaft.

3. A carbon feeding mechanism for arc

- 4
- lamps including carbon lifting means consisting of a pair of lifting rods, a cross piece connecting the upper ends of said rods, actuating means for said lifting means consisting of a pair of rocker shafts having inwardly extending offset arms, links connecting said arms with the cross piece connecting the rods, and a solenoid unit for actuating said rocker arms.
- 10 4. A carbon feeding mechanism for arc lamps including carbon lifting means consisting of a pair of lifting rods, a cross piece connecting the upper ends of said rods, a rocker shaft disposed at right angles to the rods, a bifurcated rocker arm disposed radially on said shaft and receiving one of said rods, a link connecting the rocker arm with the cross piece between the rods, and a solenoid unit for actuating the rocker shaft.
- 15 5. A carbon feeding mechanism for arc lamps including carbon lifting means consisting of a pair of spaced lifting rods, a cross piece connecting the upper ends of said rods, a pair of rocker shafts arranged at right angles to the rods, bifurcated rocker arms carried by said shafts and arranged so that the rods have a guiding engagement between the members of the bifurcated
- 20 30 35 40 50 55 60 65 70 75 80 85 90 95 100
- rocker arms, links connecting the rocker arms with the cross piece between the rods, and a solenoid unit for actuating the rocker shaft.
6. A carbon feeding mechanism for arc lamps of the multiple type including a frame, carbon lifting devices arranged in said frame to operate in parallel planes and in spaced relation, a pair of rocker shafts arranged adjacent the upper end of said carbon lifting devices, offset arms carried by said rocker shafts and operatively connecting with the carbon lifting devices, and a solenoid unit arranged between the carbon lifting devices and beneath the rocker shafts and operatively connected with the said rocker shafts to actuate the same.
7. A carbon feeding mechanism for arc lamps of the multiple type including a frame comprising upper and lower plates, supporting columns connecting said plates in spaced relation, insulated carbon guides carried by the lower plate, carbon lifting devices arranged above said carbon guides and arranged to operate in a plane parallel to the axes of the carbons, horizontally disposed rocker shafts journaled in the upper plate, rocker arms carried by said rocker shafts, links connecting the rocker arms with the carbon lifting devices, and a solenoid unit mounted on said supporting columns and operatively connected with the rocker shafts.
8. In a carbon feeding mechanism for arc lamps, carbon lifting means, a solenoid unit for actuating said lifting means, said unit including a slidably mounted solenoid, a yielding coupling carried by the armature of the solenoid and comprising bolts carried by the armature, springs on said bolts, a crosshead having a guiding engagement with said bolts and adapted to operate against the tension of the spring, and operating connections between the crosshead and the carbon lifting means.
9. In an arc lamp, a carbon feeding mechanism including a carbon holding frame having a clutch and means for actuating said frame including a solenoid, and means for yieldingly mounting said solenoid comprising rods, a solenoid carrying frame adapted to be guided on said rods, an abutment on the rods within the limits of the frame, and springs arranged between opposite frame parts and said abutments.
- In testimony whereof I hereunto affix my signature.
- EARL G. PERKINS.
